UNITED STATES PATENT OFFICE.

JOSEPH PONTEFRACT, OF NEW BRIGHTON, ASSIGNOR OF ONE-HALF TO
MATTISON DARRAGH, OF BRIDGEWATER, PENNSYLVANIA.

CARTRIDGE IMPLEMENT.

SPECIFICATION forming part of Letters Patent No. 249,986, dated November 22, 1881.

Application filed August 12, 1881. (No model.)

To all whom it may concern:

Be it known that I, JOSEPH PONTEFRACT, a citizen of the United States, and a resident of New Brighton, Beaver county, Pennsylvania, 5 have invented certain Improvements in Devices for Loading, Crimping, and Extracting Cartridge-Shells, of which the following is a specification.

My invention is a simple, cheap, and handy 10 device constructed to facilitate the loading, crimping, and extracting of the shells used for shot-guns.

In the drawings, Figure 1 is an external elevation of my improved device as arranged for 15 use in loading; Fig. 2, a plan of Fig. 1; Fig. 3, a section showing the device arranged for crimping. Fig. 4 is a view showing the device as arranged for extracting the shell from the gun-barrel; Figs. 5 and 6, views showing 20 a modification.

The tool consists of a cylindrical stock, A, about equal in diameter to that of the shell to be loaded, and provided with a head, a. To a neck, b, below the head a, are secured the upper ends 25 of a number of spring-fingers, c, which normally occupy the position shown in Fig. 1, when the tool may be used as a rammer in loading. To the end of the stock is secured detachably a button, d, and each finger c carries 30 at the inner side, at a point opposite said button, a lug, e, having a curved under face, as shown. A flat ring, f, incloses the fingers c, and when moved up to the position shown in Fig. 1 permits the fingers to spring outward, 35 but when pushed down toward the ends of the fingers it presses the latter against the stock, bringing the lugs e against the button d. The tool, as thus adjusted, may be used for crimping or inflanging the upper edge of the shell 40 by applying it to the same as shown in Fig. 2, and then revolving it while pressing the lugs e firmly upon the edge of the shell.

The tool thus formed can be constructed cheaply, and admits of easy adjustment to fit it for the different offices required. 45

The fingers c may be hinged instead of being flexible; and in place of using a detachable button, d, as described, the end of the stock may be enlarged and reduced in diameter by using a sliding sleeve, h, Figs. 3 and 4. When the 50 sleeve is down a broad end for loading is presented. When raised the reduced end of the stock presents a projection the equivalent of the button d.

For extracting the shells from the gun-barrel each finger c c c is provided with a transverse recess, i, for the introduction of the enlarged end of the shell, clamping the latter by the ring f, as shown, Fig. 4.

In place of a ring, f, a conical head or nut, 60 j, turning on a screw, k, may be forced between the ends of pivoted fingers, so as to bring the latter against the button. (See Fig. 5.)

I claim—

1. A combined loader, crimper, and extractor, 65 consisting of a stock, A, fingers c, with studs e, adapted to bear on the edge of the cartridge-case, and a sliding ring, or its equivalent, whereby to bring the fingers against the stock, and a movable button, or its equivalent, to enlarge 70 and reduce the diameter of the end of the stock.

2. A combined loader, crimper, and extractor, 75 consisting of a stock, A, longitudinal fingers c, provided with studs e and recesses i, and appliances, substantially as described, for operating the fingers, substantially as set forth.

In testimony whereof I have signed my name to this specification in the presence of two subscribing witnesses.

JOS. PONTEFRACT.
